(57) **CLAIM**

The ornamental design for a chair, as shown and described.

DESCRIPTION

FIG. 1 is a perspective view of a chair in accordance with the invention disclosed and claimed herein;

FIG. 2 is a front elevational view of the present invention;

FIG. 3 is a side elevational view of the present invention, the opposite side view being a mirror image thereof (with or without the handle shown in broken line in FIG. 1);

FIG. 4 is a rear elevational view of the present invention; and,

FIG. 5 is a top plan view of the present invention.

The broken line showing throughout the drawings is for environmental purposes only and forms no part of the claimed design.
